UNITED STATES PATENT OFFICE.

CHARLES LINKE, OF PARIS, FRANCE.

METHOD OF AND APPARATUS FOR BURNING LIQUID FUEL.

Application filed March 28, 1922. Serial No. 547,424.

To all whom it may concern:

Be it known that I, CHARLES LINKE, residing at Paris, France, a citizen of the French Republic, have invented or 5 covered certain new and useful Improvements in Methods of and Apparatus for Burning Liquid Fuel, of which improvements the following is a specification.

My invention relates to the combustion 10 of liquid fuel, petroleum for example, and consists both in method of combustion and in apparatus by which combustion is effected, that is to say, in burner construction. The object in view is to gain from 15 the fuel and make available to service a maximum quantity of heat.

The invention is illustrated in the accompanying drawings, in which Fig. 1 is a view in vertical section of a burner structure in which and in the operation of which my invention is realized. Fig. 2 is a fragmentary plan view of this burner structure, seen from above. In this figure one of the limiting walls of the combustion 25 chamber appears in horizontal section. Fig. 3 is a view in vertical section, on a plane at right angles to that of Fig. 1. Fig. 4 is again a plan view from above, showing but half of the structure, but indicating features not fully shown in Fig. 2. Fig. 5 is a view in cross-section, illustrating a detail of assembly; the plane of section is indicated in Fig. 3 by the dotted line V—V. Fig. 6 is a fragmentary view in 35 side elevation, illustrating a preferred arrangement of a manually-operable regulator. Figs. 7 and 8 are views in elevation and to larger scale of certain brushes which enter into the organization. Figs. 40 9-13 are diagrammatic, and serve to indicate the principle involved in the generation of the flame, with varying arrangements of the air supply.

My invention, broadly stated, consists in 45 projecting fluid fuel in the form of an attenuated sheet, and in causing converging streams of air or equivalent flame-nourishing gas to pick up the fuel so spread out and in so picking it up to mingle intimately 50 with it, forming immediately a mixture which, because of intimacy of union, burns at once and releases the heat where release is desired. Incidentally, I so construct my burner that, under the heat of the flame,

the passages through which the fuel and 55 the air approach the line of union are themselves highly heated. In consequence, the converging streams become heated, the fuel, initially fluid, is vaporized, or at least brought near to the condition of vapor, the 60 act of mixing is facilitated, and combustion proceeds immediately.

The projection of the fuel in the form of an attenuated sheet may conveniently be accomplished by means of a rotating disk. 65 The disk dips on one side into a pool of the liquid fuel and from the other side the liquid flies from the disk in response to centrifugal force. Referring to Figs. 1 and 3 of the drawings, a shaft 1 carried in 70 bearings 2, is rotatable by suitable means, as for example a pulley 3. Mounted integrally on the shaft is a disk 4, which dips into a pool P of liquid fuel maintained in the bottom of a chamber 6, encasing the 75 disk. The preferred arrangement is that shown; the shaft extends horizontally and the disk stands in vertical position, and at the lowest portion of its periphery dips into the pool of liquid fuel. The effect of 80 rotation of the disk is to project from its upper rim an attenuated sheet, a curtain of fluid fuel. This curtain may conceivably be physically continuous, and what the minute character of the curtain in this 85 respect may be will depend somewhat on the character and quality of the particular material employed as fuel, but practically it consists of very finely divided particles. The fuel is in fact atomized. In Fig. 3 an 90 arrow below indicates the direction of disk rotation, while the arrows above indicate the substantially tangential lines in which the fuel is projected and incidentally the 95 consequent spread of the projected curtain of material.

It will ordinarily be found desirable that the liquid in pool P be maintained at constant level. To that end, a float valve may control the supply. A convenient arrangement is that shown; a tank 17 is provided, connected to casing 6 through a pipe 18, so that liquid may rise to the same level in both casing and tank, and in this tank 17 the float of the float valve may be arranged. 100 Casing 6 may be provided further with a drain pipe 19.

The disk will ordinarily be thin, smooth

surfaced, and knife-edged, as shown, and provision will be made to regulate the quantity of liquid carried by and slung from the disk. Such regulating provision is found in 5 the brushes 14 and 15 (cf. Figs. 3, 5, 7 and 8). The brushes may be of fine wire 26 set in bodies or carriers 25. Two brushes 14 sweep the faces of the disk. They extend radially of the disk, or substantially so, and, 10 viewed transversely (Fig. 5), they are inclined toward the disk in the direction of disk motion. They are conveniently arranged opposite one another, and they are stationed above but near the place of emergence of the 15 disk from pool P, and near and somewhat below the horizontal diameter of the disk. They are carried on arms which extend through the wall of the casing, and they may from the outside be nicely adjusted. They 20 will not ordinarily bear upon the disk surfaces, but they will be so spaced as to sweep from the disk all surplus liquid, beyond the quantity required for proper operation. Brush 15 wipes the edge of the disk (the 25 brush being flexible conforms to the shape of the edge), and brush 15 is accessible for adjustment through an opening 16 in the casing wall. A swinging door may close this opening while the apparatus is in operation.

It is manifest that, as the disk coated with a film of liquid rotates, the liquid, acquiring momentum from the disk, accumulates at the periphery, and is thence slung off along substantially tangential lines; and it is manifest that, in the arrangement illustrated, the effect of the forces acting upon the liquid is to cause the throwing off of the attenuated curtain of liquid chiefly from the ascending 40 upper quadrant, that is the upper left-hand quadrant, as seen in Fig. 3.

An opening in the upper wall 21 of the casing provides for the projection vertically upward from the casing of such an attenuated curtain of fuel. This opening extends from a point substantially in vertical line above the extreme edge of the disk on the left (Fig. 3) in left to right direction. Within the casing a shield 20 carries back to the 50 pool any liquid that may be thrown from the disk later in the course of rotation. Brush 15 and shield 20 are so placed that the projected curtain of fuel does not impinge upon either end of the wide-open slot.

55 The effective extent of the slot in casing wall 21 may be controlled by a stepped shield 13. This shield is in form a partial cylindrical shell, pivoted on the cylindrical axis and adapted to be adjusted manually. 60 As shown in the drawings this shield is wholly withdrawn and out of the way, and the slot in the casing is free throughout its length. But comparison of Figs. 1 and 3 will show that as this shield is swung (anti-clockwise, Fig. 1) the effective length of the

slot will be diminished step by step, from left to right as seen in Fig. 3. A stop 27 may be provided to prevent reduction of the effective length of this slot beyond a minimum necessary to maintain combustion.

70

Two converging streams of air entrain between them the attenuated curtain of fuel projected from casing 6. These streams of air are projected each through a line of orifices. Mixing takes place at once, and combustion immediately follows. The orifices of the two lines may be set in opposite succession, as shown in Figs. 2 and 9, or in the staggered arrangement shown in Fig. 10. In the one case the impact of the opposite jets of air is direct, and the effect is a relatively tall and slender flame; in the other case there is an interlacing of the air jets and the flame is shorter and broader. This is indicated by the arrows in the drawings. The orifices through which the jets of air are delivered may extend in lines perpendicular to the line of meeting, as in Figs. 2, 4, 9, 10, and 12, or in lines oblique to the line of meeting, as in Figs. 11 and 13, and, as 90 will be apparent, such obliquity may be in one direction at one end of the line and in opposite direction at the other end of the line. These and other such variations in the formation and assembly of the air orifices 95 may be adopted, with corresponding modification in the shape of the flame. Variability in the shape of the flame adapts the invention to service conditions of different sorts.

100

I preferably form the air orifices as outwardly tapering orifices 11 in tuyère blocks 9, which tuyère blocks 9 when set side by side form a continuous air header chamber 8. From chambers 8 the orifices 11 lead. The opposite lines of orifices 11 are preferably oppositely and equally inclined to the vertical as best shown in Fig. 1. The tuyère blocks 9 are so shaped that when assembled in opposite lines the two lines form between them a continuous upwardly tapering passageway 10. The casing 6 with its contained disk is arranged beneath the double line of tuyères, with the slot in the upper wall of the casing exactly in line beneath passageway 10, so that the curtain of fuel projected in vertical plane from casing 6 shall be projected through passageways 10 toward the meeting line of the two converging streams of air (each air stream compounded of a 110 line of jets).

115

The tuyère blocks are formed preferably of refractory material, such as fire brick, and constitute part of the floor of the combustion chamber, as is clearly apparent in Figs. 1 and 2. The flame springs from the line of union and of mixing of fuel and air, and the effect of burning is that these tuyère blocks become highly heated. This is advantageous for the entering streams of air and 120 125 130

of fuel are heated as they approach the line of meeting and mixture and combustion are in consequence accelerated. The fuel in attenuated form being so heated approaches or 5 passes beyond the point of vaporizing, and thus lends itself with greater facility to mixture and combustion.

The tuyère blocks are so particularly shaped that when the assembly is made the 10 passageway 10 increases in length from its lower end toward its upper, as is shown in Fig. 3. Thus the free spread of the projected curtain is provided for.

The air is projected from orifices 11 under pressure, and, while the arrangement is 15 not necessarily such, I find it convenient to drive the streams of air by instrumentalities deriving their power from the same rotating shaft 1 which drives disk 4. To this end 20 two fans 5 are mounted on shaft 1, one on either side of casing 6. These fans, taking in air through their heads deliver the air at their peripheries, and drive it in streams through uptake passageways 7 which feed 25 the air header chambers 8 in the two lines of tuyère blocks 9.

With such an arrangement the casing 6 may be kept secure against the entrance of air, for at the points 8, where the shaft 1 30 passes through the casing walls the fans exert suction, and, instead of allowing ingress of air, to the extent that opportunity for leakage exists, the flow is of fuel vapor outward,—not of air inward. The presence 35 of small quantities of fuel vapor in the streams of air is in no degree objectionable. There can therefore be no back fire within casing 6.

Dampers 12 may be provided in air uptake 40 passageways 7, and these dampers, like shield 13 may be in the form of partial cylindrical shells rotatable on their cylindrical axes. The two dampers may be provided with means for shifting them by hand; they 45 may be interconnected, to be shifted in unison; and they may further be interconnected with shield 13, so that proportionately as the quantity of fuel delivered to the place of combustion is diminished, the quantity of 50 air delivered may be proportionately diminished. Such interconnection is indicated in Fig. 6. Cranks 22 extend from the axles of the cylindrical dampers 12 and crank 23 extends from the axle of cylindrical shield 13. 55 These cranks are interconnected by links 24, and the whole may be shifted as a unit by the handle which crank 23 carries. A projecting index travelling over a dial may serve to indicate the degree of opening of 60 the stepped shield 13 and of the correspondingly moving dampers. The linked connection admits, of course, of adjustment.

It will be understood that the burner now described is so related to other apparatus as 65 to supply heat to useful ends. Ordinarily

the space above into which slot 9 and ducts 11 discharge is the combustion chamber of a furnace of one sort or another.

The burner is operated by rotation of shaft 1. As it rotates an attenuated curtain of fuel is projected vertically upward from casing 6 through passageway 10 toward the line of impact of the convergent streams of air which at the same time are projected through the two lines of orifices 11. The ascending fuel entering the heated region between the tuyère blocks 9 is, in addition to being already drawn out into attenuated form, further prepared for combustion by being elevated in temperature toward or beyond its point of vaporization. The air also is by heating prepared for combustion. It is further prepared for intimate mingling by the form given to the two streams by virtue of passage each through a line of orifices. These two streams so projected are not of uniform intensity throughout the breadth of the stream, but points of greater intensity alternate with points of less. This is effected by projecting the streams of air 80 in opposite series of jets. The upwardly-directed convergent streams of air have a suction effect, cooperating with or super-added to the initial propelling force which drives the fuel and readily draw or entrain the fuel between them. The air and the fuel so brought together mingle intimately, and the mixture burns with great rapidity, delivering up at the desired place relatively 90 large quantities of heat.

Manifestly increase of speed of rotation (with adjustment if necessary of brushes 14 and 15) means increased delivery both of fuel and of air to the combustion chamber, with consequent release of increased quantities of heat.

I have mentioned petroleum as suitable fuel; lighter oils, petroleum derivatives and other oils may be used; heavier oils too may be used. If normally too viscous, the oil used 105 may be rendered more fluid by preheating. Ordinarily air will be used to effect combustion, but in exceptional circumstances other combustion-sustaining gas may be employed, —pure oxygen, for instance. When in the 110 ensuing claims I speak of liquid fuel and of air, I desire to be understood as contemplating all the range of substances here alluded to.

In its broader aspects the invention is not 115 limited to the details here presented by way of example.

I claim as my invention:

1. The method herein described of burning liquid fuel which consists in projecting 120 against gravity and into the line of meeting of convergent streams of combustion-sustaining air an attenuated curtain of fuel.

2. The method herein described of burning liquid fuel which consists in projecting 125

against gravity and into the line of meeting of convergent streams of combustion-sustaining air an attenuated curtain of fuel, and heating the fuel as it is projected.

5. 3. The method herein described of burning liquid fuel which consists in projecting under centrifugal force and into the line of meeting of convergent streams of combustion-sustaining air an attenuated curtain of fuel.

10. 4. The method herein described of burning liquid fuel which consists in projecting to the line of meeting of convergent series of jets of air an attenuated curtain of fuel, whereby a combustible mixture of said components is formed.

15. 5. In a fluid fuel burner means for sling- ing centrifugally an attenuated curtain of fuel, and means for maintaining streams of air convergent from opposite sides upon the curtain of fuel so projected.

20. 6. In a fluid fuel burner a combustion chamber through whose floor is formed a vertically disposed passageway, means for sling- ing centrifugally an attenuated curtain of fuel vertically through said passageway and into said combustion chamber, means for maintaining streams of air convergent from opposite sides upon the curtain of fuel

30. so projected.

35. 7. In a fluid fuel burner means for sling- ing centrifugally and against gravity an attenuated curtain of fuel, and means for maintaining upwardly directed streams of air convergent from opposite sides upon the curtain of fuel so projected.

40. 8. In a burner for liquid fuel the combination of means for projecting the fuel against gravity in the form of an attenuated curtain and means for projecting convergent streams of air on either side of such curtain, substantially as described.

45. 9. In a burner for liquid fuel the combination of a vertically slotted body of refractory and heat-radiating material, means for projecting an attenuated curtain of fuel upward through that slot and means for projecting from either side convergent streams of air into the path of the fuel beyond the slot, substantially as described.

50. 10. In a burner for liquid fuel the combination of a receptacle, a rotatable disk arranged to dip into a pool of liquid maintained in said receptacle, means for regulating the amount of liquid carried on the surface of said disk, and means for maintaining a stream of flame-nourishing air, the means last named and the disk being so relatively placed that fluid slung centrifugally from the perimeter of the disk is slung into the air stream.

55. 11. In a burner for liquid fuel the combination of a receptacle, a rotatable disk arranged to dip into a pool of liquid main- tained in said receptacle, means for remov-

ing from the surface of the disk superfluous quantities of fuel and means for maintaining a stream of flame-nourishing air into which fuel from the rim of the disk is on rotation of the disk centrifugally slung.

70

12. In a burner for liquid fuel the combination of a fuel receptacle, a disk mounted in vertical position for rotation and arranged to dip at its lower margin into a pool of fuel maintained in said receptacle, and means for directing upwardly converging streams of air from opposite sides into the plane in which the disk extends and to a line of meeting above the upper margin of the disk, substantially as described.

80

13. In a burner for liquid fuel the combination of two converging rows of oppositely inclined air ports, means for projecting jets of air through such ports, and means for projecting an attenuated curtain of fuel into the angle formed by and between the air jets, substantially as described.

85

14. In a burner for liquid fuel the combination of a slot, means for projecting through said slot an attenuated curtain of fuel, means for varying the effective length of the slot, and means for aerating the fuel beyond said slot.

90

15. In a burner for liquid fuel the combination of a casing having in its lower part a receptacle for liquid fuel, and in its upper part a delivery slot, a rotary shaft extending through and beyond the casing, a disk borne integrally by the shaft and arranged within the casing, and adapted to dip into a pool of liquid fuel contained therein, and on rotation to impel an attenuated curtain of fuel through said slot, a fan wheel borne integrally by the shaft and arranged externally of the casing, and an air passageway and an orifice through which air is caused to flow on rotation of said fan wheel.

100

16. In a burner for liquid fuel the combination of a casing, a rotary shaft extending horizontally through and beyond the casing, a rotary disk borne integrally by said shaft and arranged vertically within the casing, fan wheels with central intake eyes arranged, one on either side and externally of and adjacent to said casing and borne integrally by said shaft, said casing forming in its lower part a receptacle for a pool of liquid fuel into which said disk is arranged to dip, a slot in said casing above and in line with the plane of disk extent, air passageways leading upward from said fans and terminating in orifices through which on rotation of the shaft convergent streams of air are driven to a meeting point above and in the plane in which said disk extends, substantially as described.

110

17. In a burner for liquid fuel the combination of a casing having in its lower part a receptacle for liquid fuel and in its upper part a delivery slot, a rotary disk arranged

120

- within the casing, adapted to dip into a pool of liquid fuel contained therein and on rotation to impel an attenuated curtain of fuel through said slot, an air passageway 5 arranged to deliver air to the fuel impelled through said slot, means for varying the effective length of said slot, and a damper in said air passageway, said damper and said means for varying the effective extent of the 10 slot being articulated together and movable in unison, substantially as described.
18. In a burner for liquid fuel the combination of a rotary disk, means for main-
- taining a pool of liquid fuel into which the disk in the range of its rotation may dip, 15 brushes arranged adjacent said disk after emergence from such pool, and means for maintaining convergent streams of air adjacent said disk, substantially as described.
- In testimony whereof I have hereunto set 20 my hand.
